(57) **CLAIM**

The ornamental design for a cookware base, as shown and described.

DESCRIPTION

FIG. 1 is a bottom, rear, left-side, perspective view of a cookware base;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a bottom plan view thereof;

FIG. 7 is a bottom, rear, left-side, perspective view thereof;

FIG. 8 is a front elevation view thereof;

FIG. 9 is a rear elevation view thereof;

FIG. 10 is a left-side elevation view thereof;

FIG. 11 is a right-side elevation view thereof;

FIG. 12 is a bottom plan view thereof;

FIG. 13 is a bottom, rear, left-side, perspective view thereof;

FIG. 14 is a front elevation view thereof;

FIG. 15 is a rear elevation view thereof;

FIG. 16 is a left-side elevation view thereof;

FIG. 17 is a right-side elevation view thereof;

FIG. 18 is a bottom plan view thereof;

FIG. 19 is a bottom, rear, left-side, perspective view thereof;

FIG. 20 is a front elevation view thereof;

FIG. 21 is a rear elevation view thereof;

FIG. 22 is a left-side elevation view thereof;

FIG. 23 is a right-side elevation view thereof; and,

FIG. 24 is a bottom plan view thereof.

(Continued)

In the drawings, the broken lines are for the purpose of illustrating portions of the cookware base, and form no part of the claimed design.
